No. 786,658.

PATENTED APR. 4, 1905.

B. L. MERRILL.

LADDER.

APPLICATION FILED DEC. 10, 1903.

UNITED STATES PATENT OFFICE.

BUEL L. MERRILL, OF LITCHFIELD, MAINE.

LADDER.

SPECIFICATION forming part of Letters Patent No. 786,658, dated April 4, 1905.

Application filed December 10, 1903, Serial No. 184,631.

To all whom it may concern:

Be it known that I, BUEL L. MERRILL, a citizen of the United States, residing at Litchfield, in the county of Kennebec and State of Maine, have invented certain new and useful Improvements in Ladders; and I do hereby declare the following to be a full, clear, and exact description of the invention, such as will enable others skilled in the art to which it appertains to make and use the same.

This invention has particular reference to extension-ladders, and especially to such as are designed for assuming the form of a step-ladder; and the object in view is the provision of means in combination with such extension-ladder for locking the parts thereof in their given relations.

With this and further objects in view the invention consists in combination, with a plurality of ladder-sections, of means connecting said sections together and permitting longitudinal movement thereof with respect to each other and a cam carried by one of said sections for engaging the other of said sections for locking the same against movement.

It further consists in certain other novel constructions, combinations, and arrangements of parts, as will be hereinafter fully described and claimed.

In the accompanying drawings, Figure 1 represents a perspective view of a ladder embodying the features of the present invention and illustrated as positioned for forming a step-ladder. Fig. 2 represents a similar view of the same extended. Fig. 3 represents an enlarged detail perspective view of the locking mechanism.

Referring to the drawings by numerals, 1 indicates a lower, 2 an intermediate, and 3 an upper, section. To the sides of the lower section 1 are secured depending hooks 4, adapted to engage the sides of the section 2, said sides of section 2 being spaced apart a distance slightly less than the distance apart of the 5 sides of section 1, whereby the section 2 is adapted to slide longitudinally between the sides of section 1, supported and guided by the hooks 4. The lower ends of the sides of section 2 carry hooks 5 bent outwardly, upwardly, and about the respective sides of the

lower section 1, whereby the lower ends of the sides of section 2 are guided in their longitudinal movement. The sides of section 2 on their upper edges are formed with lock-receiving notches 6, preferably semicircular in form and adapted to receive locking-cams 7, carried by a rotatably-mounted rung 8, forming part of section 1. The cam 7 at one end of rung 8 is formed with a flat-faced projecting dog 9, adapted in operation to engage the 60 flat upper edge of its respective side of section 2 for locking its cam against rotation, and thereby preventing longitudinal movement of the said section. Both of the cams 7 are fixed to the rung 8, and the cam opposite 65 that carrying dog 9 is provided with an operating-handle 10, formed with a flat undersurface adapted to engage the upper edge of the corresponding side of section 2 for limiting the given cam against rotation, and thus locking the said side against longitudinal movement when said cam is within one of the notches 6. Section 3 is pivotally connected to straps 11 70 11, said straps being fixed to section 2 near the upper end thereof, and a hook 12 is employed for locking the upper rung of section 2 to the lower rung of section 3 for retaining the said sections in proper position when extended. A hook 13 is hung from one of the 75 rungs of section 2 and is adapted to engage one of the rungs of section 3 when said section 3 is lowered for forming an inclined support for sections 1 and 2.

In operation, when it is desired to cause the sections to assume the extended condition illustrated in Fig. 2, section 2 is moved longitudinally of section 1 as far as desired and the cams 7 are permitted to drop within a set of notches 6, whereby said sections are locked in their given relation. The section 3 is next 80 raised on its pivots, and hook 12 caused to engage a rung of section 2 and a rung of section 3. The ladder is then in condition for use. When it is desired to change the ladder from this position to a folded-up position, it is only 85 necessary to remove the hook 12 and rotate the cams 7 by grasping handle 10 and pulling the same outwardly. As soon as the cams 7 have moved out of the notches 6 the 90 section 2 is free to be slid longitudinally of 95 section 1, and the sections are then folded up. 100

section 1, and the sections may be locked in a closed position by turning the cams 7 into the uppermost notches of section 2. The section 3 may be swung upon its pivots into contact with section 2, and the parts will be in their most compact form. From this form the ladder may be changed to the step type by simply swinging the section 3 outwardly to a plane at an acute angle to the longitudinal plane of the other sections and securing said section 3 in position by dropping the hook 13 over one of the rungs of the same.

Having thus fully described my invention, what I claim as new, and desire to secure by Letters Patent, is—

1. In a device of the class described, the combination with slidably-connected ladder-sections, of a cam pivotally carried by one of said sections, and lying contiguous to one edge of the other section, said second-mentioned section being formed with a notch in that edge next to said cam, of a size and shape designed to receive the cam, and means to limit the rotation of said cam in one direction.
2. In a device of the class described, the combination with a plurality of slidably-connected ladder-sections, one of said sections being formed with a notch, of a cam pivotally carried by the other of said sections and adapted to fit within said notch, and a laterally-projecting dog extending from said cam and adapted to engage the notch-section for preventing rotation of the cam.
3. In a device of the class described, the combination with a plurality of slidably-con-

nected ladder-sections, one of said sections being formed with a notch, of a cam pivotally carried by the other of said sections and adapted to fit within said notch, and means for preventing rotation of said cam in one direction while within the notch.

4. In a device of the class described, the combination with a plurality of slidably-connected ladder-sections, one of said sections being formed with a notch in its upper surface, of a cam pivotally carried by the other of said sections and positioned for swinging in a vertical plane parallel to the longitudinal axis of said ladder-sections and adapted to be swung within the said notch for locking the sections against longitudinal movement with respect to each other, and means for preventing rotation of said cam in one direction while within the notch.

5. In a device of the class described, the combination with a plurality of slidably-connected ladder-sections, of a rotatably-mounted rung carried by one of said sections, a cam projecting laterally from said rung and positioned for swinging in a vertical plane parallel to the longitudinal axis of said ladder-sections when said rung is rotated, the other ladder-section having one of its side rails lying in the path of movement of said cam.

In testimony whereof I hereunto affix my signature in presence of two witnesses.

BUEL L. MERRILL.
